UNITED STATES PATENT OFFICE.

FRANK H. BUCK AND PHILIP MCRAE, OF WILMINGTON, DELAWARE, ASSIGNOR TO THE JESSUP & MOORE PAPER CO., OF PHILADELPHIA, PENNSYLVANIA, A CORPORATION OF MASSACHUSETTS.

ELECTROLYTIC CELL.

Original application filed December 5, 1925, Serial No. 73,447. Divided and this application filed March 8, 1927. Serial No. 173,731.

This application is a divisional of my co-pending application Serial No. 73,447, filed December 5, 1925.

Our present invention relates to a cell of the electrolytic type which is adapted to the production of caustic soda and other products, such as chlorine and hydrogen.

While the cell of this invention is particularly adapted for the production of those reagents, yet obviously, it may be used in the electrolysis of many materials.

The principal object of the invention is the provision of a cell of the above type which will have a maximum capacity for a minimum cell volume in order that a given amount of floor space may be utilized for as large a number of cells as possible, and where a compact design reduces the internal resistance to a minimum, thus increasing the power efficiency.

To this end the invention includes a cell casing of any desired material adapted to support a cathode in the form of a perforated iron basket, which cathode is also provided with an inner portion upstanding from the bottom of the main basket and spaced from the basket side walls. The inside of the outer cathode basket and the outside of the inner cathode cage are lined with asbestos or other material serving as a diaphragm, which when assembled, forms two channels into which anode slabs of graphite or the like are inserted, the slabs being spaced from the walls of the cathode and from each other so as to allow thorough circulation of the electrolyte as well as to increase the anode surface. A suitable head is provided adapted to clamp between itself and the cell casing the cathode and the diaphragm in a gas tight joint. The head forms what may be called a gas chamber from which the gaseous products of the electrolytic action may be removed for any desired purpose. An additional outlet is provided for the gaseous products collecting in the space between the cathode and the cell casing, and still another outlet at the bottom of the casing for liquid products, from which outlet they may be conducted to any desired location. Means are also provided for automatically feeding in the electrolyte so as to

maintain a constant electrolyte level in order that the operation of the cell may be continuous.

The invention further includes an outer cathode in which the shorter end walls are removable therefrom, as well as the inner cathode cage, so as to facilitate the placing of new and the removal of old diaphragms thereto.

The invention further consists of the novel arrangement, construction and combination of parts hereinafter shown and described.

We have illustrated in the accompanying drawings an embodiment of our invention, in which:

Figure 1 is a side elevation.

Fig. 2 is a plan view of the device of Fig. 1.

Fig. 3 is a sectional elevation of the device of Fig. 1.

Fig. 4 is a detail of the outer cathode basket. 70

Fig. 5 is a detail of the inner cathode cage.

Referring now with particularity to the drawings, our invention is shown to consist of an outer cell casing designated at 1, which may be of any desired material, which is suitably mounted upon insulators 2 resting upon blocks or pedestals 3.

At the upper edges of the side walls of the casing 1 we provide angle irons 4 suitably bolted to the wall of the casing 1, which are adapted to support a flange 5 on the side walls of the outer cathode basket, indicated generally at 6.

The outer cathode member is composed of sheets of perforated metal, preferably iron, in the present instance, welded together to form an open topped container or basket having flanges 5 at its upper ends, which flanges are adapted to rest upon and be supported by the angle irons 4.

The outer cathode member is provided with removable end walls 42 adapted to be made secure to the longitudinal walls 43 by engagement with flanges 44, and bolted thereto.

Within the outer cathode member is located an inner cathode member or cage indicated generally at 7, which also consists of sheets of perforated iron welded together to form substantially a cage. Secured inside the cage cathode 7 we provide a section of U beam 8, 100

which beam is provided with bolts 9 extending through the bottom of the cathode cage 7. The bolts 9 are adapted to project through corresponding apertures 10 in the cathode basket 6 and a similar section of U beam 11 applied to the bottom of the basket 6 whereupon nuts 12 may be used to bolt the basket and the cage together to form substantially a unitary structure.

10 Similar bolts 40 are provided in the end walls 39 of this inner cathode cage and which project through apertures 41 in the removable end walls 42 of the cathode basket 6.

A diaphragm 13 of sheet asbestos or the like, is to be applied to the inside of the cathode basket 6 and the outside of the cathode cage 7, as by means of sodium silicate or the like, so that the entire surface of the electrolyte containing channel is covered by said 20 diaphragm.

By making the end walls 42 of the cathode basket removable, the application of the diaphragm is greatly facilitated. It is to be understood that the diaphragm may be applied to the face of end wall 42 and this member then bolted in place against the flanges 44.

At the upper longitudinal edges of the basket cathode 6 we provide bus bars 14, which bars may be of iron, copper, or other material, and welded, brazed, or otherwise affixed to the flanges 5. This bus bar 14 serves as 30 the negative electrode.

A gas chamber or head 15 is provided, which is composed preferably of a molded 35 form of concrete or the like, and is adapted to be superimposed upon the upper edges of the basket cathode 6 so that the lower edges of the gas head 15 rest directly upon the diaphragm 13 which over-laps the bus bars 14. 40 The lower edges of the gas head 15 are cut away as at 16, and this channel is adapted to be filled with any desired kind of acid-proof cement so that when the head is placed upon the bus bars 14 the cement within the 45 channel will make a fluid tight resistant joint at that point.

The gas head which we have found advantageous consists of a box, open at the bottom and top, the top of which is adapted to be 50 closed by section covers 17, 18 and 19, resting upon a shoulder 20 at the upper edges of the gas head walls. The center section cover 18 is provided with a clean-out opening 21. It is understood that all of the joints in the gas 55 head are adapted to be sealed, not necessarily permanently, with a cement of any desired character, which is well known in this art, so as to prevent the escape of any gaseous products of the electrolysis.

60 The anode element of the present cell consists principally of a plurality of carbon slabs 22 which are supported upon the section covers 17, 18, and 19 by means of pins 23 passing through the slabs, the slabs proper 65 projecting through suitable apertures in the

cover sections and extending into the space between the basket and cage cathodes nearly to the bottom thereof, and spaced from the walls thereof by means of the rubber stops 24. The upper ends of the anode slabs are connected together as by means of the positive bus bar 25, to which current is supplied as desired.

Supported upon an L-iron 26 secured to the outside wall of the cell casing is a float container 27 which is adapted to receive the float 28 having a stopper or valve 29 connected thereto to control the flow of electrolyte supplied through the inlet 30. Such float and valve is adapted to maintain a constant level 80 in the float receptacle 27, said electrolyte flowing from the float receptacle into the interior of the cell through the aperture 31.

A gas offtake 32 penetrating one of the section covers 19, is provided for conducting away the chlorine produced as a result of the desired reaction, said offtake being connected with a main conduit 33.

A pipe 34 is also secured in the wall of the casing 1 so as to take care of any gaseous products liberated on the outside of the diaphragm 13, that is, between the diaphragm and the outer cell casing. This pipe 34 also connects with a conduit 35 so that the gases thus produced may be taken away.

The cell casing proper, 1, is provided with a trap 36 through which the liquid material produced as a result of the reaction may flow, a ditch 37 conducting this material to the desired location.

The operation of the device is as follows:

A saturated solution of sodium chloride is fed through the inlet 30 until the level of electrolyte in the cathode has risen well up into the gas head. Owing to the fact that the 105 cathode basket and cage are lined with an asbestos diaphragm, the electrolyte will not pass through this material, but will be contained therein.

Upon completing the circuit the sodium 110 chloride in solution will be decomposed, the chlorine migrating to and being liberated at the surface of the carbon electrodes so that the gas as such rises through the electrolyte into the gas head and passes out of the offtake 115 32 into the conduit 33. The sodium of the sodium chloride migrates through the diaphragm covering the basket and cage cathodes, to the cathode, and is there liberated, and as soon as liberated, reacts with the water present to form caustic soda and hydrogen. The hydrogen being on the casing side of the diaphragm, passes through the perforated cathode and out of the pipe 34 provided for that purpose. The liquid caustic 120 soda drips from the bottom of the basket cathode and passes out of the trap 36 into the drain or ditch 37.

The action is continuous by reason of the 125 fact that the float 28 allows the valve 29 to be

opened as soon as the level of the electrolyte within the cell has lowered.

In the claims where the term end wall appears, it is intended to cover the wall of 5 shorter dimensions. Where the term side wall occurs, it is intended to cover any of the vertical walls.

We claim:

1. An electrolytic cell comprising a container, an outer cathode basket therein, an inner cathode cage within the basket and of the full length thereof, two electrolyte chambers being formed between corresponding walls of the cathode members, diaphragms lining 15 said chambers and an anode extending into each chamber.

2. An electrolytic cell comprising a container, an outer cathode basket therein, an inner cathode cage within the basket, said 20 cathode basket having removable end walls, said cathode cage being of the full length of the cathode basket, the side walls of the cage abutting the end walls of the basket, two electrolyte chambers between cage and basket, 25 diaphragms lining said chambers and an anode extending into each chamber.

3. An electrolytic cell comprising a container, a perforated cathode therein comprising four vertical parallel walls, removable 30 end walls at right angles thereto secured to the ends of the vertical walls thus forming three parallel chambers, means to feed the electrolyte to the two outside chambers, diaphragms lining the said chambers and anodes 35 dipping into the outside chambers.

4. An electrolytic cell comprising a container, a cathode suspended therein, said cathode comprising two spaced apart parallel electrolyte containing chambers, a diaphragm 40 lining each chamber, the four sides and bottom of each chamber being active, a chamber free from electrolyte located between the electrolyte chambers, and anodes projecting into the electrolyte chambers.

45 5. An electrolytic cell comprising a container, a cathode suspended therein, said cathode comprising parallel electrolyte containing chambers, a diaphragm lining each chamber, an active cathode wall separating said chambers, a gas head supported upon the outer walls of the cathode, the division wall of the cathode terminating short of the top of the gas chamber top, the division wall being adapted to be submerged in the electrolyte, and anodes projecting into the electrolyte chambers.

60 6. An electrolytic cell comprising a container, a cathode therein, said cathode comprising parallel electrolyte containing chambers, a diaphragm lining each chamber, an active cathode division therebetween comprising a substantially inverted U portion of the full length of the electrolyte chambers, end walls closing the electrolyte chambers and inverted U portion, a gas head supported

upon the outer walls of the electrolyte chambers, and anodes projecting into said chambers.

7. An electrolytic cell comprising a container, a cathode therein comprising spaced 70 apart electrolyte containing chambers, a diaphragm lining each chamber, spaced apart dividing cathode walls between the electrolyte chambers, one dividing wall comprising one wall of an electrolyte chamber, the two 75 spaced apart dividing walls being closed at the top, a diaphragm covering the electrolyte chambers and dividing walls and top, common end walls closing the electrolyte chambers and dividing walls, and anodes projecting 80 into the electrolyte chambers.

8. An electrolytic cell comprising a container, a cathode therein comprising spaced apart electrolyte containing chambers, a diaphragm lining each chamber, a chamber free 85 from electrolyte of the full length of the electrolyte chambers and located between the said electrolyte chambers, end walls closing said chambers, a gas head supported upon the outer walls of the cathode and anodes 90 projecting into the electrolyte chambers.

9. An electrolytic cell comprising a container, a cathode therein comprising spaced apart longitudinal walls forming two spaced 95 apart electrolyte containing chambers, a diaphragm lining each chamber, said chambers being closed by active bottom and end walls, a central longitudinal chamber of the full length of the electrolyte chambers, and closed at the top, a gas head resting upon the outer 100 walls of the cathode, the electrolyte chambers being non-communicative as to the electrolyte until the level of the electrolyte rises above the central longitudinal chamber, and anodes projecting into the electrolyte chambers.

10. An electrolytic cell comprising an outer cathode basket, an inner cathode cage within the basket and of the full length thereof, two electrolyte chambers formed by the corresponding walls of the cathode members lined 110 with a diaphragm and anodes extending into each chamber and means beneath the cathode to receive liquid effluent dripping therefrom.

11. An electrolytic cell comprising an outer cathode basket, and inner cathode cage within the basket, the cathode basket having removable end walls, said cathode cage being the full length of the cathode basket, the side walls of the cage abutting the ends walls 120 of the basket, two electrolyte chambers between the cage and the basket, a diaphragm lining therefor and anodes extending into each chamber and means beneath the cathode to receive liquid effluent dripping therefrom.

12. An electrolytic cell comprising a cathode forming two spaced apart parallel electrolyte containing chambers, a diaphragm lining therefor, the four sides and bottom of each chamber being active, a chamber free 130

from electrolyte located between the electrolyte chambers, and anodes projecting into the electrolyte chambers and means beneath the cathode to receive liquid effluent dripping therefrom.

13. An electrolytic cell comprising a cathode having spaced apart electrolyte containing chambers, a diaphragm lining therefor, a chamber free from electrolyte of the full length of the electrolyte chambers, and located between the said electrolyte chambers and walls closing said chambers, a gas head supported upon the outer walls of the cathodes, and anodes projecting into the electrolyte chambers and means beneath the cathode to receive liquid effluent dripping therefrom.

In testimony whereof, we affix our signatures.

FRANK H. BUCK.
PHILIP McRAE.
